S. A. REEVE.
MUSICAL NOTATION.
APPLICATION FILED JULY 14, 1919.

1,415,396.

Patented May 9, 1922.

Sidney A. Reeve Inventor

UNITED STATES PATENT OFFICE.

SIDNEY ARMOR REEVE, OF NEW BRIGHTON, NEW YORK.

MUSICAL NOTATION.

1,415,396.

Specification of Letters Patent. Patented May 9, 1922.

Application filed July 14, 1919. Serial No. 310,635.

To all whom it may concern:

Be it known that I, SIDNEY A. REEVE, a citizen of the United States, and resident of New Brighton, in the county of Richmond 5 and State of New York, have invented certain new and useful Improvements in Musical Notation, of which the following is a specification.

This invention relates to musical notation 10 for pianoforte, organ or orchestral score, and constitutes an improvement upon my earlier invention in the same field, application for patent for which was filed Nov. 23, 1918, Serial No. 263875, and now co-pending 15 (resulting later in Patent 1,313,015, issued Aug. 12, 1919). The general advantages sought and gained are fully stated in the earlier application.

In this earlier patent the general inventive idea is defined, amongst other ways, 20 as consisting of a staff the horizontal lines of which are spaced like the black keys of the pianoforte-keyboard, with noteheads of contrasted form so located thereon that, 25 amongst other things, it shall be accomplished that "in the open spaces of the great staff, where there is preferably only a single guide-line per octave, no two noteheads of similar form shall occur within sufficient 30 propinquity to confuse the eye or mind as to the pitch intended."

In this earlier application the particular embodiment of this idea illustrated there 35 showed a staff on which, in each octave, the notes A, D and G natural were represented by square or rectangular noteheads, B, C, E and F by triangular noteheads, A-sharp, C-sharp, D-sharp and F-sharp by circular noteheads, and G-sharp by a diamond-shaped or 40 oblique square notehead. But this arrangement, while embodying the general idea quoted, did not bring out its best possibilities. It is the office of this present invention to improve upon the earlier invention 45 in this respect.

In the drawing of this present application the great staff is shown as composed 50 of two single staves, each having five lines grouped by two and three, like the spacing of the black keys of an octave of pianoforte-keyboard. The space between the two single staves is just sufficient for a third, intermediate set of five lines like each of 55 these single staves (with proper space between sets), but of this third set only one

line—that corresponding to A-sharp—is shown. This line is called the guide-line. Above and below the great staff super-treble and contra-bass octaves are similarly represented, where needed, each by a single A- 60 sharp guide-line.

In the drawing the guide-lines (one for each octave) are marked A# at the right-hand end. The various notes are marked with their names, over a sufficient range to 65 cover all doubts.

On this great staff A, D and G natural are represented by square or rectangular noteheads, and B, C, E and F natural by triangular noteheads, as in the earlier invention. But, because of possible confusion or error when so many as four tones in 70 each octave are represented by circular noteheads, as in the earlier invention, such forms are used herein only for A-sharp, C-sharp 75 and F-sharp. Both D-sharp and G-sharp are represented by diamond-shaped or oblique square noteheads.

The advantage of this is visible in the spaces between, above or below the single 80 staves, where only a single guide-line per octave is used. Referring first to the circular form of notehead, one of these, in each octave, is located directly upon the guide-line. Each of the others stands clear from the line, 85 yet sufficiently near it so that there is no possibility of its confusion with the next circular notehead above or below, associated with an adjacent guide-line.

Similarly as to the diamond-shaped noteheads, one of them in each octave is so nearly 90 below the guide-line, while the other is about midway between the two widely spaced A-sharp lines above and below, that confusion between the two notes is impossible. 95

I claim:

1. A musical notation comprising a plurality of horizontal lines relatively spaced like the black keys of the pianoforte-keyboard, with the twelve half-tones of each 100 octave indicated by noteheads of four contrasted forms, one such form being used for the white keys A, D and G natural, a second form for the white keys B, C, E and F natural, a third form for three out of the 105 five black keyboard-keys, and the fourth form for the remaining two black keyboard-keys, substantially as described.

2. A musical notation comprising a plurality of horizontal lines relatively spaced 110

like the black keys of the pianoforte-keyboard, with rectangular noteheads to indicate the notes A, D and G natural, triangular noteheads to indicate the notes B, C, E and 5 F natural, circular noteheads to indicate A-sharp, C-sharp and F-sharp, and diamond-shaped noteheads to indicate D-sharp and G-sharp, substantially as described.

Signed at New Brighton, Staten Island, in the county of Richmond and State of 10 New York this tenth day of July, A. D. 1919.

SIDNEY ARMOR REEVE.
